(57) **CLAIM**

The ornamental design for a potty training device as shown and described.

DESCRIPTION

FIG. 1 is a front-to-rear perspective view of a portion of a potty training device, showing our new design;

FIG. 2 is a rear-to-front perspective view thereof;

FIG. 3 is a right side elevational view thereof, the left side elevational view thereof being a mirror image;

FIG. 4 is a front elevational view thereof;

FIG. 5 is a rear elevational view thereof;

FIG. 6 is a top plan view thereof; and,

FIG. 7 is a bottom plan view thereof.

The broken lines represent portions of the potty training

device that form no part of the claimed design.
